UNITED STATES PATENT OFFICE.

CHARLES G. ARMSTRONG AND CHARLES A. DRESSER, OF CHICAGO,
ILLINOIS, ASSIGNEES TO G. A. EDWARD KOHLER AND FRANKLIN
W. KOHLER, OF CHICAGO, ILLINOIS.

ELECTRICAL DOOR-OPENER FOR ELEVATORS.

No. 814,928.

Specification of Letters Patent.

Patented March 13, 1908.

Application filed April 3, 1901. Serial No. 54,132.

To all whom it may concern:

Be it known that we, CHARLES G. ARMSTRONG and CHARLES A. DRESSER, citizens of the United States, residing at Chicago, in the county of Cook and State of Illinois, have invented a certain new and useful Improvement in Electrical Door-Openers for Elevators, of which the following is a full, clear, concise, and exact description, reference being had to the accompanying drawings, forming a part of this specification.

Our invention relates to electrical door-openers for elevators, our object being to provide means whereby the elevator door or doors may be effectively and conveniently opened through the agency of electrical energy.

Our invention contemplates the opening of doors at the landings as well as the opening of a door or doors carried upon the car.

Our invention has been particularly developed with reference to elevator-cars having double doors and in connection with a system having double doors at the landings, and we have illustrated our invention in connection with such structures. It will be understood, however, that our invention is equally applicable to other arrangements.

We have illustrated our invention in the accompanying drawings, in which—

Figure 1 is a view of an elevator-car equipped with our invention. Fig. 2 is a plan view thereof. Fig. 3 is a detail view of the door-closing device. Fig. 4 is a detail view of a portion of the door-opening device.

Like letters refer to like parts in the several figures.

The elevator-car *a* is provided with doors *h* and *h'*, which slide on tracks *l* and *l'* by means of rollers *m m*. The doors *h* and *h'* are provided with uprights *k* and *k'*, respectively, which are braced by braces *k²* and *k³*, respectively. The uprights *k* and *k'* are pivoted to levers *e²* and *e³*, respectively.

Mounted on top of the elevator-car *a* is a solenoid *b*, which is energized by current entering by conductors *c c*, which conductors are connected with any suitable source of electricity. A switch *j* is provided at a convenient position in the elevator-car *a* for controlling the circuit through the solenoid. Solenoid *b* has two cores *b'* and *b²*, which are

mounted so that when the solenoid is energized said cores will be drawn into the solenoid. The cores *b'* and *b²* are fastened to lever-arms *e* and *e'*, respectively, by links *d* and *d'*. The springs *g* and *g'* retract the lever-arms *e* and *e'* when the solenoid is deenergized. Lever-arm *e* is mounted on pivot *f* and attached at one end to spring *g* and link *d* or door-lever *d* and at the other end to lever-arm *e²*, so that when lever-arm *e* moves lever-arm *e²* moves therewith, thereby opening or closing the door *h*, as the case may be. The same is true of lever-arm *e'*, which is mounted on pivot *f'* and attached at one end to spring *g'* and link *d'* and at the other end to lever-arm *e³*, so that when lever-arm *e'* moves lever-arm *e³* moves therewith, thereby opening or closing the door *h'*, as the case may be.

Mounted on the doors *h* and *h'* are lugs *i* and *i'*, which are superimposed one above the other, lug *i* being above lug *i'*. As the doors *h* and *h'* open these lugs *i* and *i'* engage shoulders *i²* and *i³*, respectively, said shoulders being mounted on the inside of doors *h²* and *h³* at the landing, thereby opening the doors *h²* and *h³*, situated at the landing. Should the solenoid be energized while the car is above or below the landing, the lugs *i* *i'* will fail to engage the shoulders *i²* *i³*, and thus although the inner or car doors will be opened, the doors at the landing will remain closed. The stopping of the car properly at the landing is thus insured, as otherwise the doors at the landing are not opened.

The device for closing the shaft-doors at the landing may take any of the usual forms, and, as shown in Fig. 3, comprises a rope *o*, passing over a pulley *o'* and secured at one end to a weight *n*. The door *h³* is provided with a similar rope *o''*, passing over pulley *o''* and carrying weight *n'*.

It will be understood that while we have shown a specific form of mechanism for conveying motion from the solenoid-core to the door any approved mechanism may be employed. Moreover, any form of door-closing mechanism may be substituted for that shown. Furthermore, instead of employing a hand-switch for controlling the circuit through the solenoid the circuit through the solenoid may be controlled in any other preferred manner. Instead of a solenoid having

two movable cores any other form of solenoid may be used and the solenoid may be replaced by an electromagnet with stationary core and movable armature, or, in fact, by 5 any electrically-operated device.

It will be seen that the door associated with the elevator-shaft and through which the passengers pass to and from the elevator is provided with a shielding or protecting device, as it were, located between it and the operator of the car and constituting the doors h h' , and that it is this shielding or protecting device that is connected with the electromagnet, so as to be moved; that there is means 10 for connecting this shielding or protecting device with the door of the elevator-shaft when the car is in a predetermined position and is stopped in that position, and that the efforts of the operator to open the door under 15 any other conditions—such, for example, as when the car is moving and it would be dangerous to the passengers—would be without success, for his efforts would result simply in moving the shielding or protecting device, and this would not permit the passengers to 20 pass in or out of the car or get in a position of danger during this process. It will further be seen that while the operator thus has under his control a means for preventing passengers from passing from or into the car—namely, the shielding device, which he can 25 keep closed—he has taken from him the power to bring about conditions which will let the passengers pass to and from the car except 30 when a condition of safety is assumed.

Having described our invention, what we claim as new, and desire to secure by Letters Patent, is—

1. The combination with an elevator-car 40 of an electromagnetic device located on said car, a movable door also mounted on the car, an operative connection between said door and the electromagnetic device by means of which the door may be opened, a door at the 45 elevator-landing, and a detachable connection between the two doors whereby both doors may be simultaneously opened by the electromagnetic device under predetermined conditions.

2. The combination with an elevator-car 50 of an electromagnetic device carried thereby, a movable door mounted upon the car, an operative connection between said movable door and the electromagnetic device, a door 55 at the landing, normally independent of said electromagnetic device, and means for bringing said latter door under the influence of said electromagnetic device under predetermined conditions.

3. The combination with an elevator-car 60 of two sliding, separating doors mounted on the car, a solenoid also mounted upon said car, two independent cores therefor, each of 65 said cores operatively connected with one of the sliding doors on the car, a retracting de-

vice for each of said cores, and means on the car for controlling the position of said cores substantially as described.

4. The combination with an elevator-car, of an electromagnetic device thereon, a door 70 carried upon said car, a door at the landing, means for connecting said electromagnetic device with the door carried upon the car, and a part mounted upon the car-door for engaging and opening the door at the landing, 75 substantially as described.

5. The combination with an elevator-car of a sliding door carried thereby, an electromagnetic device mounted upon the car and operatively connected with said door so as to 80 control the same, a door at the landing normally independent of said electromagnetic device on the car, and means for connecting the door at the landing with said electromagnetic device as the car moves up and down. 85

6. The combination with an elevator-car, of a pair of doors, a single electromagnetic device mounted upon the car, and intermediate mechanism between said electromagnetic device and said doors, whereby both of said doors are opened when the electromagnetic device is actuated, substantially as described. 90

7. The combination with an elevator-car, of a solenoid carried thereon, a pair of car-doors carried upon said car, a pair of cores for 95 said solenoid, one at each end thereof, and intermediate mechanism between each of said cores, and one of said doors, whereby the doors are opened when the solenoid is energized, substantially as described. 100

8. The combination with an elevator-car, of an electromagnetic device carried thereon, a car-door, intermediate mechanism between said car-door and said electromagnetic device so that the said door can be opened by 105 the electromagnetic device, a door at the landing inaccessible to the operator when the car-door is closed, and a part carried upon said car-door for engaging said door at the landing, the engaging parts being constructed 110 so that the door at the landing can be opened only when the car is in the immediate vicinity of the landing, whereby the door at the landing is beyond the direct control of the operator, substantially as described. 115

9. The combination with an elevator-car, of a solenoid mounted thereon at the top of the car, a car-door, a pivoted lever above the head of the car operator and having one end connected with said door and the other end connected with the core of said solenoid, and a retracting device for retracting said core, substantially as described. 120

10. The combination with an elevator-car, of an electromagnetic device carried thereon, 125 a switch carried upon said car in convenient location to be reached by the operator, a door, also on the car, and intermediate mechanism between said door and said electromagnetic device, comprising a series of hori- 130

zontally-disposed connecting-pieces, substantially as described.

11. The combination with an elevator-car, of a solenoid carried thereon, a pair of car-doors carried upon said car, a pair of cores for said solenoid one at each end thereof, and a lever between each of said cores and one of the doors, whereby when the solenoid is energized both doors are opened, substantially as described.

12. The combination with an elevator-car, of a pair of car-doors located upon the car, a pair of doors at the landing out of reach of the operator when the car-doors are closed, and a single electromagnetic means carried upon the car for opening both pairs of doors, substantially as described.

13. The combination with an elevator-car, of a pair of car-doors upon the car, a pair of doors at each landing, the doors on the car shielding the doors on the landing so that they cannot be directly operated by the operator, a single electromagnetic device mounted upon the car for opening both pair of doors, and means whereby the landing-doors can be opened only when the car is in the immediate vicinity thereof, substantially as described.

14. The combination with an elevator-car, of a pair of car-doors carried upon the car, a pair of doors for each landing shielded from the direct control of the operator by the doors on the car, outwardly-projecting lugs or arms upon the car-doors, inwardly-projecting lugs or portions upon the landing-doors, the said car-door lugs being adapted to engage the landing-door lugs when the car is in the vicinity of the landing, whereby the landing-doors are opened by the opening of the car-doors and a single electromagnetic device carried upon the car to open said car-doors, substantially as described.

15. The combination with an elevator-car, of a solenoid at the top of said car, a pair of doors carried upon the car and horizontal levers extending between the solenoid and the

top of said doors to open them, substantially as described.

16. The combination with an elevator-car, of a solenoid horizontally mounted upon and carried at the top of the car, a pair of cores for said solenoid, one at each end thereof, a pair of doors carried upon the car vertical posts or standards secured to said doors, and a horizontal lever extending between each solenoid-core and the vertical post or standard upon one of the doors, substantially as described.

17. The combination with an elevator-car of two sliding separating doors mounted thereon, a solenoid above the doors provided with two independent horizontally - positioned cores, each provided with suitable retracting devices, a pivoted angularly-disposed solenoid-lever connected with each core and projecting toward the said doors, a connecting-piece pivotally connected with each solenoid-lever, said connecting-pieces connected with the doors near the meeting faces, and means for energizing and deenergizing said solenoid so as to control the position of said doors.

18. The combination with an elevator-car of an electromagnetic device carried thereby, a door associated with the elevator-shaft, a shielding or protecting device between said door and the car operator, a connection between said shielding or protecting device and said electromagnet, so that the shielding or protecting device may be moved, and means for connecting said shielding or protecting device with the door associated with the elevator-shaft when the car is opposite the landing.

In witness whereof we have hereunto subscribed our names in the presence of two witnesses.
